PLANE

Filed Dec. 5, 1922

UNITED STATES PATENT OFFICE.

THOMAS T. TVEDT, OF BROOKLYN, NEW YORK.

PLANE.

Application filed December 5, 1922. Serial No. 605,010.

This invention relates to planes and more particularly to planes of the general character disclosed in applicant's application Serial Number 516,908, filed November 22, 1921.

5 The plane shown and described in this application comprises a small thin blade mounted so that it may be quickly and easily removed from the plane and discarded when it becomes dull and a sharp blade inserted 10 in place thereof.

One object of the present invention is to produce a combination of elements comprising a small thin cutting blade which may be substituted as a unit for the iron in 15 planes at present in commercial use.

Another object of the invention is to provide a novel and improved construction for clamping the small thin blade in position.

With these and other objects in view the 20 invention comprises the novel and improved constructions, arrangements and combinations of parts hereinafter described and particularly pointed out in the claims, the advantages of which will be readily understood 25 and appreciated by those skilled in the art.

The invention will be clearly understood from the accompanying drawings illustrating the invention in its preferred form and the following detailed description of the 30 constructions therein shown.

In the drawings—

Fig. 1 is a view partly in side elevation and partly in vertical section illustrating a plane embodying the invention;

35 Fig. 2 is a detail view of the iron blade and inner clamping plate detached from the plane taken in the direction of the arrow *a* Fig. 1;

Fig. 3 is a detail perspective view illustrating the parts shown in Fig. 2;

40 Fig. 4 is a perspective view of the removable blade; and

Fig. 5 is a sectional view illustrating a modified form of inner clamping plate.

45 In the embodiment of the invention illustrated in the drawing, the plane comprises a stock 2 having the usual handle 4 and stud 6 to be grasped by the operator in operating the plane. The stock is formed with an opening 8 through which the blade 50 projects below the lower surface of the stock and with an inclined face 10 upon which the iron rests.

In the preferred form of the invention

the blade is mounted on the lower end of 55 the iron and is secured thereto by a clamping plate so that iron, blade and clamping plate may be inserted in and removed from the plane as a unit. The blade consists of a relatively small thin somewhat flexible piece 60 of sheet steel preferably having at least two cutting edges and mounted in the plane so that it may be quickly and easily reversed or removed from the plane. Blades of this character may be cheaply manufactured so 65 that they may be thrown away when they become dull thereby eliminating the necessity of grinding blades which, in the ordinary plane, takes a great deal of labor and time.

In the construction shown, the iron is indicated at 12 and the blade at 14. This blade is provided with two cutting edges and is mounted on the lower end of the iron so that these edges may be placed alternatively in cutting position, the blades resting on 70 the upper face of the iron as shown in Figs. 1 and 3. The blade, as stated above, is somewhat flexible so that it requires support adjacent its cutting edge. The blade is supported on its rear side adjacent its cutting edge by the forward end of the iron which extends comparatively close to the cutting edge of the blade and the blade is located in a predetermined and definite position 75 with relation to the forward end of the iron 80 by means of two pins 16 arranged to engage 85 in openings 18 in the blades.

The blade is clamped in position on the iron preferably by means of a clamping plate 20 bearing at its forward end on the 90 blade and secured to the iron by means of a screw 22 passing through a slot 24 in the iron and threaded into the clamping plate 20. The blade is supported on its forward side adjacent its cutting edge by the forward 95 end of the clamping plate which is placed so that it engages the blade comparatively close to its edge. The clamping plate may be adjusted longitudinally of the iron to locate the forward end thereof in the desired 100 position with relation to the blade, upon loosening the holding screw 22. To prevent the blade from chattering when the plane is in use, the forward end of the clamping plate 20 is bowed as shown clearly in Figs. 105 1 and 3, the rear of the bowed portion of the plate engaging the blade adjacent its rear edge as shown in these figures.

The iron, blade and clamping plate 20 of the present construction take the place of the usual iron with integral cutting edge. These parts are arranged to be adjusted as 5 a unit to adjust the blade with relation to the stock. The adjusting means comprises a lever 26 pivoted at 28 on the stock, the upper end of which lever is arranged to project through a slot 30 in the clamping 10 plate 20. The lower end of the lever 26 engages in a groove in a manually adjustable nut 31 threaded on a stud 32 secured in the plane stock. The movement of the inner clamping plate produced by the movement of 15 the nut 31 and lever 26 adjusts the iron, blade and inner clamping plate unit longitudinally with relation to the stock.

The iron, blade and inner clamping plate unit is held in adjusted position with relation to the stock by means of an outer clamping plate 34 secured to the stock by means of a screw 36 passing through a slot 37 in the plate 34, a slot 38 in plate 20 and through the slot 24 in the iron and threaded into the 20 stock. The clamping plate 34 is arranged to tilt about the head of the screw 36 in a plane substantially perpendicular to the plane of the iron and is curved in cross section so that it engages at its forward end the forward end 25 of the inner clamping plate. The rear end of the outer clamping plate is adjusted outwardly to force the forward end thereof into clamping engagement with the inner clamping plate by means of a lever 39 pivoted at 40 on said plate and provided with a cam shaped bearing portion arranged to engage a spring plate 42 interposed between the lever and the inner clamping plate 20. This spring plate is secured at its lower end 30 to the clamping plate 34 and, by its bearing against the clamping plate 20, yieldingly holds the iron, blade and clamping plate in position when the pressure of the outer clamping plate 34 on the inner clamping 35 plate is relieved by the actuation of the lever 39.

In Fig. 1 of the drawing, the parts are shown in operating position, the lever 39 having been operated to force the forward 40 end of the clamping plate 34 into clamping engagement with the forward end of the inner clamping plate 20. The engagement of the outer clamping plate 34 with the inner clamping plate not only holds the iron, blade, and inner clamping plate unit securely 45 in position in the stock, but also forces the inner clamping plate more firmly against the blade to clamp the blade securely to the iron. The engagement of the inner clamping plate with both the forward and rear edges of the blade holds the blade in a reliable manner and obviates any tendency of the blade to tilt about the lower end of the iron when in use.

65 The construction shown in Fig. 5 differs

from that shown in Figs. 1, 2 and 3 in that the inner clamping plate indicated at 42 is made of a size substantially the same as that of the bowed portion at the lower end of the clamping plate 20. The clamping plate 42 70 as shown in Fig. 5 is preferably made slightly less in width than the blade and is secured to the iron 12 by means of screws 44 passing through holes in the plate and the holes 18 in the blade and threaded into the 75 iron. By reason of its bowed form in cross section the clamping plate 42 securely clamps the forward and rear edges of the blade against the iron.

The plane construction above described, 80 with the exception of the iron blade and inner clamping plate unit, is substantially the same as that of certain planes now in commercial use, this unit having been substituted for the iron of such planes. When it is desired to adjust this unit in the plane the lever 39 is actuated to relieve the pressure of the clamping plate 34 on the inner clamping plate and the said unit may be then adjusted by turning the adjusting nut 31. 90

When a blade becomes dull and it is desired to reverse or replace the same, the lever 39 is actuated to relieve the pressure of the clamping plate 34 on the inner clamping plate and the clamping plate 34 is then removed; the slot 37 having an enlargement at one end to permit the head of screw 36 to pass therethrough. The iron, blade and inner clamping plate unit is then removed and the inner clamping plate and iron are disconnected by loosening the screw 22 and relatively manipulating the parts so that the head of the screw will pass through an enlargement in the slot 24. The blade, if only one edge is dulled, may be reversed in position on the iron, or, if both edges are dulled, it may be discarded and a sharp blade substituted therefor. The change in the blade thus may be quickly and easily made and the blade is clamped securely in position 100 when in use. Whichever form of inner clamping plate is employed, the blade is supported adjacent its cutting edge on one side by the iron and on the other by the clamping plate. 110

When a blade having two cutting edges is employed the openings 18 are located centrally of the blade so that either edge thereof may be located in a predetermined and definite position with relation to the iron by 120 the engagement of the pins 16 in said openings.

Having explained the nature and object of the invention and having specifically described a construction embodying the invention in its preferred form, what is claimed is—

The combination of a bench plane iron, clamp plate and small thin bit or blade; the clamping plate having a bowed front clamp- 130

ing portion of such width relative to the bit or blade that when its front edge engages said bit near the cutting edge in the cutting position of the latter, the other side of the 5 bowed portion engages the bit adjacent the rear edge so that the bit is resiliently clamped and held adjacent both edges, the

bit and iron having inter-engaging pins and openings to properly locate its edge to be clamped.

Signed at New York, N. Y., this 2nd day of December, 1922.
